Primary Examiner—Louis S. Zarfas*Assistant Examiner*—Catherine R. Oliver*Attorney, Agent, or Firm*—Dennis W. Beech[57] **CLAIM**

The ornamental design for a rectangular crate organizer, as shown and described.

DESCRIPTION

FIG. 1 is a top side perspective view of the rectangular crate organizer showing my new design;

FIG. 2 is a side elevation view of the invention thereof;

FIG. 3 is an front elevation view thereof;

FIG. 4 is an rear elevation view thereof of the end opposite FIG. 3;

FIG. 5 is a side elevation view thereof of the side opposite FIG. 2;

FIG. 6 is a bottom plan view thereof;

FIG. 7 is a top plan view showing the interior two pocket and three pocket sides thereof;

FIG. 8 is a side cross-sectional view showing an elevation view of the interior three pocket side thereof; and,

FIG. 9 is a side cross-sectional view showing an elevation view of the interior two pocket side of my new design.

The broken line showing of the rectangular crate in FIGS. 1 through 6, 8 and 9 and the tools in FIG. 1 is for illustrative purposes only and forms no part of the claimed design.
